(57) **CLAIM**

The ornamental design for a vehicle front bumper, as shown and described.

DESCRIPTION

FIG. 1 is a front perspective view of the vehicle front bumper; FIG. 2 is a left side elevation view thereof the right side being a mirror image of that side shown; FIG. 3 is a top plan view thereof; and,

FIG. 4 is a front view thereof. The portions of the vehicle shown in broken lines are for illustrative purposes only and form no part of the claimed design.
